UNITED STATES PATENT OFFICE.

ZACHARY T. HALL, OF PHILADELPHIA, PENNSYLVANIA.

DESIGN FOR A PIPE-COLLAR AND FLUE-STOPPER.

SPECIFICATION forming part of Design No. 19,016, dated April 9, 1889.

Application filed March 9, 1889. Serial No. 302,654. Term of patent 14 years.

To all whom it may concern:

Be it known that I, ZACHARY T. HALL, a citizen of the United States, residing in the city and county of Philadelphia, State of

5 Pennsylvania, have invented and produced a new and original Design for a Pipe-Collar and Flue-Stopper, of which the following is a specification, reference being had to the accompanying drawing, forming part thereof.

10 The leading feature of my design for a pipe-collar and flue-stopper is a circular row of dots around the inner bead of the breast.

In the drawing, A designates a pipe-collar and flue-stopper. Around the inner periph-

ery of the breast B is a bead, C, within which 15 is a circular row of dots, D. The breast has on its face a row of radiating figures, E, of elliptical form.

I claim—

15 A design for a pipe-collar and flue-stopper 20 having a breast, a bead on the inner periphery thereof, and a circular row of dots within said bead, substantially as shown and described.

ZACHARY T. HALL.
